His Attorney.

UNITED STATES PATENT OFFICE.

FRED L. STONE, OF SCHENECTADY, NEW YORK, ASSIGNOR TO GENERAL ELECTRIC COMPANY, A CORPORATION OF NEW YORK.

ELECTRIC HOIST.

1,347,303.

Specification of Letters Patent.

Patented July 20, 1920.

Application filed August 26, 1919. Serial No. 320,006.

To all whom it may concern:

Be it known that I, FRED L. STONE, a subject of the King of Great Britain, residing at Schenectady, in the county of Schenectady, State of New York, have invented certain new and useful Improvements in Electric Hoists, of which the following is a specification.

My invention relates to electric hoists and the like and it provides improved means whereby the hoist brake may be controlled in a safe, reliable and efficient manner.

My invention is particularly useful in connection with electric mine hoists, although it is generally applicable to all types of electric hoists, elevators and the like.

In the operation of electric hoists it is desirable that the brake for the hoist be applied when the power fails, but under certain conditions it is undesirable that the brake be applied immediately upon the failure of power. Thus, for instance, in the case of a mine hoist, of the slope type where one or more cars are hauled up an incline, when the hoist is lowering cars it is desirable that the brake be applied substantially simultaneously with the failure of power, but when the hoist is operating in the hoisting direction it is not desirable to apply the brake simultaneously with the failure of power, since the cars have considerable inertia and will continue up the slope for some considerable distance, depending upon the inclination of the slope and the stored energy in the load being hoisted. The drum being stopped, the load being hoisted will eventually come to rest and start back down the slope so that when the rope has been drawn taut, the rope will either break, pull out of the shackle, or the draw bars between the cars will break, so that the entire trip or part of it will start down the slope and cause a serious accident.

One of the objects of my invention is to provide improved means whereby on failure of power the brake will not be applied until after the speed of the hoist has been considerably reduced. Preferably the application of the brake should occur simultaneously with the stopping of rotation of the hoist drums, the arrangement being such, however, that during lowering, with or without the electric motor energized, failure of power

will apply the brakes practically instantaneously.

Where the hoist is of the balanced type in which there is a double track slope with a loaded trip going up on one track and an empty trip going down on the other track, the hoist brake will not be applied until the speed of the hoist has been very materially reduced or the hoist drum has stopped rotating.

For a better understanding of my invention, reference is had to the accompanying drawings wherein I have shown my invention embodied in concrete form for purposes of illustration, and in which Figure 1 shows diagrammatically an electric hoisting system provided with my invention, and Fig. 2 is a detail of Fig. 1, showing a part section of an over-running clutch which is adapted to drive in one direction only.

Referring to Fig. 1, for purposes of illustration I have shown an electric motor 10 of the induction type adapted to drive the hoisting drum 11 through the pinion and gear shown. The motor is energized from a source of supply 12 by means of reversing contactors 13 and 14, the coil circuits of which are controlled by means of a master controller 15, in a well-known manner. The motor is provided with a wound rotor with secondary resistance R which may be varied in any suitable and well-known manner in order to vary the speed of the hoist. For purposes of illustration I have shown a fluid pressure brake but it will be understood by those skilled in the art that my invention is equally applicable to other well-known types of brakes. The brake B shown is of the gravity set type and a fluid pressure releasing mechanism is provided. This mechanism comprises a piston 16 operating in a cylinder 17 which receives a fluid under compression from the reservoir 18 through the rotary valve mechanism 19. In the position shown in the drawing the valve is in the position in which the fluid is exhausted from the cylinder 17 to atmosphere through the port 20. An operating mechanism for effecting the application and release of the brake B is provided, and this operating mechanism comprises a lever 21 fulcrumed at its mid-point and connected to the operating lever 22 of the valve 19 by

means of a link 23. The plunger 24 of a no-voltage protective electromagnet having an operating coil 25 coöperates with the right-hand end of the lever 21 and a speed responsive device 26 of the well-known fly-ball governor type coöperates with the left-hand end of the lever 21. The lever 21 is biased to its upper position at which the brake is released, by means of the spring 21'. 10 The fly-ball governor is driven through bevel gears 27 from the shaft 28 to which the hoisting drum 11 and the brake B are connected. An over-running clutch 29, shown in more detail in Fig. 2 is provided for driving the fly-ball governor only when the hoist is operating in the hoisting direction. This over-running clutch comprises a ratchet wheel 30 connected to the shaft 31 which drives the fly-ball governor and a sleeve 32 15 connected to the shaft 33 which is driven from the shaft 28 through the bevel gears 27. This sleeve 32 is provided with a plurality of rollers or balls 34 which coöperate with the sleeve 32 and the ratchet wheel 30 to drive the fly-ball governor when the hoist is operating in the hoisting direction but the construction is such that when the hoist is operating in the lowering direction the rollers or balls 34 are in the position shown 20 in Fig. 2 at which the sleeve 32 is free to rotate without driving the ratchet wheel 30. This overrunning clutch is of a well-known construction, and it is thought that it need not be further described. 25 As thus constructed and arranged, the operation of my invention is as follows: Let it be assumed that it is desired to hoist the load, which for purposes of illustration has been shown as a cage 35. The pilot switch 36 will be closed so as to energize the coil 25 of the no-voltage protective electromagnet, thereby causing the plunger 24 to be raised to its elevated position, and the lever 21 to be tilted to the position indicated in 30 dotted lines at 37. The link 23 will thereby be raised and the operating lever 22 of the valve 19 will be turned clockwise so that fluid under compression is admitted to the cylinder 17 from the reservoir 18 through the pipes 38 and 39, thereby causing the piston 16 to be raised and the brake B to be released. The controller 15 will be turned 35 to the right so as to energize the reversing contactor 14 to close and connect the motor 10 to the source of supply 12. As soon as the hoist begins rotating, the fly-ball governor 26 will be caused to rotate through the rollers or balls 34 of the clutch 29 wedging themselves between the sleeve 32 and the 40 cam surfaces of the ratchet wheel 30. The fulcrum of the lever 21 will be moved upward a slight distance, but this will have no effect on the brake B, since the brake has been previously released through the energization of the coil 25. If the power should

fail while the hoist is proceeding in the upward direction, the coil 25 will be deenergized and the plunger 24 will drop and tilt the lever 21 to the position indicated in dotted lines at 40. The brake will not be applied immediately, however, since the fly-ball governor 26 is still being rotated and the fulcrum of the lever 21 has not been moved downward far enough to operate the valve 19 so as to exhaust the fluid under compression from the cylinder 17. The application of the brake will be delayed until the fluid from the cylinder 17 is exhausted through the port 20 of the valve 19 when the speed of the hoist has been very materially reduced or the hoist has been brought substantially to rest through the medium of the fly-ball governor lowering the lever 21 to the position shown in the drawings. 75

To operate the hoist in the lowering direction, the controller 15 is turned to the left so as to energize the reversing contactor 13 to close and connect the motor 10 to the source of supply 12 so as to operate in the reverse direction. The fly-ball governor 26 will be at rest since the construction of the over-running clutch 29 is such that when the hoist is operating in this direction the governor will not be driven. The lever 21 will assume the position indicated in dotted lines 80 at 37 at which fluid under compression is admitted to the cylinder 17 so as to release the brake B. In case the power should fail when the hoist is operating in the lowering direction, the brake will be applied practically simultaneously by reason of the plunger 24 of the no-voltage protective electromagnet dropping to its lower position, that shown in the drawings. The cylinder 17 will thereupon be connected to atmosphere 85 through the port 20, and the brake will be applied practically simultaneously with the failure of power. 90

In case the hoist is of the balanced type in which a trip of cars or other load is being hoisted up one slope and a trip of cars or other load is being lowered simultaneously on another set of tracks, the over-running clutch 29 will not be used, but the fly-ball governor 26 will be connected so as to rotate 95 at all times when the hoist is in operation. In this case the brake B will never be applied immediately upon failure of power but always after the speed of the hoist has been decreased to the predetermined value. 100

What I claim as new and desire to secure by Letters Patent of the United States, is:

1. The combination with an electric hoist or the like and a brake for the same, of means for automatically applying the brake 110 on failure of power, and means for delaying the application of the brake until the speed of the hoist has decreased to a predetermined value. 115

2. The combination with an electric hoist 120

or the like and a brake for the same, automatically applied on failure of power, of automatic means for preventing the application of the brake until the speed of the hoist has 5 decreased to a predetermined value.

3. The combination with an electric hoist or the like and a brake for the same, of means for automatically applying the brake on failure of power, and means operated 10 responsively to the speed of the hoist for delaying the application of the brake on failure of power until the speed of the hoist has decreased to a predetermined value.

4. The combination with an electric hoist 15 or the like and a mechanical brake for the same, of means operated responsively to the speed of the hoist and to a failure of power for delaying the application of the brake when the power fails until the speed of the 20 hoist has decreased to a predetermined value.

5. The combination with an electric hoist or the like and a mechanical brake for the same, of automatic means operated responsively to the speed of the hoist during hoisting 25 but unresponsive to the speed of the hoist during lowering for delaying the application of the brake until the speed of the hoist has decreased to a predetermined value when the power fails during hoisting, and for applying the brake simultaneously with a failure 30 of power when the hoist is lowering.

6. The combination with an electric hoist or the like and an electromagnetically controlled mechanical brake for the same, of automatic means for applying the brake simultaneously 35 with a failure of power when the hoist is lowering, and for delaying the application of the brake until the speed of the

hoist has decreased to a predetermined value when the power fails during hoisting. 40

7. The combination with an electric hoist or the like and a brake for the same, of means for effecting an application of the brake comprising a lever biased to a position at which the brake is released, a speed responsive device operating on one end of the lever and a power responsive device operating on the other end of the lever, whereby in response to a failure of power the lever is moved against its bias to effect an application 45 of the brake after the speed of the hoist has decreased to a predetermined value.

8. The combination with an electric hoist or the like and a brake for the same, of means for effecting the application of the 50 brake comprising a lever biased to a position at which the brake is released, a speed responsive device operating on one end of the lever and a power responsive device operating on the other end of the lever, and 55 means for operating the speed responsive device only when the hoist is operating in the hoisting direction, whereby in response to a failure in power the lever is moved against its bias to effect an application of 60 the brake after the speed of the hoist has decreased to a predetermined value when the hoist is operating in the hoisting direction and an application of the brake is effected 65 practically simultaneously with the failure of power when the hoist is operating in the lowering direction.

In witness whereof I have hereunto set my hand this 25th day of August, 1919.

FRED L. STONE.
